UNITED STATES PATENT OFFICE.

THEODOR KUNDTZ, OF LAKEWOOD, OHIO.

DESIGN FOR A DRAWER FOR SEWING-MACHINE CABINETS.

SPECIFICATION forming part of Design No. 35,805, dated March 11, 1902.

Application filed November 15, 1901. Serial No. 82,458. Term of patent 7 years.

To all whom it may concern:

Be it known that I, THEODOR KUNDTZ, a citizen of the United States, residing at Lakewood, in the county of Cuyahoga and State of Ohio, have invented and produced a new and original Design for a Drawer for Sewing-Machine Cabinets and other Furniture having Drawers, of which the following is a specification, reference being had to the accompanying drawings, forming a part thereof.

Figure I is a view in perspective of a drawer, showing my new design. Fig. II is a top plan of the drawer. Fig. III is a bottom plan of the drawer. Fig. IV is a rear end elevation of the drawer.

Referring to the drawings, *a* designates the inner side wall of the drawer; *b*, the outer side wall; *c*, the rear end wall; *d*, the forward end wall, and *e* the bottom of the drawer. The end walls *c* and *d* curve, as at 8, toward the outer side wall *b*, which has its central portion 10 curving or bulging outwardly and has the swell formed by the said outward bulging of the said side wall *b* extending more than one-third of the length of the

drawer. The outer side wall *b* bulges or swells outwardly, as at 12, at each end of its outwardly-curved portion 10 between the curves 8 and 10.

The leading or material feature of my design consists of the unitary design shown in the illustration and comprising a curvature 8 of the drawer between the end walls and outer side wall of the drawer, the outward swell of the central portion of the outer side wall of the drawer, and the outward bulging 12 between the curves 8 and the ends of the central outward bulge of the said side wall.

Having described my invention, what I claim as new, and desire to secure by Letters Patent, is—

The design for a drawer as herein shown and described.

Signed by me at Cleveland, Ohio, this 9th day of November, 1901.

THEODOR KUNDTZ.
